[57] CLAIM

The ornamental design for a candy, as shown and described.

DESCRIPTION

FIG. 1 is a perspective view of a first embodiment of a candy showing my new design;

FIG. 2 is a top plan view thereof;

FIG. 3 is a left side elevational view thereof;

FIG. 4 is a right side elevational view thereof;

FIG. 5 is a front elevational thereof;

FIG. 6 is a rear elevational view thereof;

FIG. 7 is a bottom view thereof; and,

FIG. 8 is a perspective view of a second embodiment thereof.

All views of the second embodiment are identical to the views of the first embodiment with the exception of the eyes.
